TOOL

Filed Oct. 26, 1928

UNITED STATES PATENT OFFICE

ALWIN G. STEINMAYER, OF MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

TOOL

Application filed October 26, 1928. Serial No. 315,284.

This invention relates to certain new and useful improvements in portable tapering tools, and refers more particularly to a tool adapted to taper the ends of conduits used in connection with underground electric systems at the time of installation.

As is well known, conduits of this nature are supplied in sections of fixed lengths which very often must be cut to accommodate particular installations, and therefore, it is desirable to provide an improved means for readily tapering the freshly cut ends of a conduit at the time of installation to facilitate its assembly with the usual coupling members.

15 A tool for this purpose is illustrated in a co-pending application of William Beauregard, Serial No. 319,601 filed November 15, 1928, and while it functions satisfactorily, it has several disadvantages, principal of 20 which is the fact that, due to its having but a single cutting edge, chattering can not be eliminated and also it is extremely difficult to hold the conduit against rotation. Therefore, this invention has as one of its 25 objects to improve the construction of tapering tools of the character described, and to provide a plurality of cutters adapted to be rotated about the end of a conduit.

Another object of this invention resides in 30 the provision of a tool of the character described in which means are provided for positively guiding the conduit between a plurality of rotating cutting members.

35 And a further object of this invention resides in the provision of means for automatically feeding the conduit between the cutting members.

40 And a still further object of this invention resides in the provision of a conduit tapering tool which is readily portable and in which the ends of conduits may be quickly and efficiently tapered.

45 With the above and other objects in view which will appear as the description proceeds, my invention resides in the novel construction, combination and arrangement of parts substantially as hereinafter described and more particularly defined by the appended claims, it being understood that such

changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles, and in which:

55 Figure 1 is a view, partly in section and partly in elevation, illustrating my improved tapering tool with a conduit in position to have its end tapered;

60 Figure 2 is a view similar to Figure 1 illustrating the rotating member in elevation and showing the manner of automatically feeding the conduit to the cutters, and

65 Figure 3 is a cross-sectional view taken through Figure 1 on the plane of the line 70 3-3.

70 Referring now more particularly to the accompanying drawings, in which like numerals designate like parts throughout the several views, 5 represents a mounting member having a base 6 which may be provided with any suitable means for attachment to a support or which may be enlarged at its bottom to form a ground engaging surface. The mounting member 5 is substantially 75 cup-shape and has an internal ring gear 7 on its outer periphery with which pinions 8 of a pair of cylindrical cutter members 9 mesh.

80 The cutter members 9 are rotatably carried by a spindle member 10 having an enlarged medial portion 11, and a bearing shaft 12, the medial portion 11 being recessed, as at 11', to receive the cutters. The axes of the cutter members are disposed at an angle to provide the desired taper and the cutter members are freely rotatably 85 mounted in the recess 11' by screws 13 which have their inner ends threaded in apertures 14 in the enlarged portion 11 and are rotated by their pinions 8 in a planetary fashion, upon the rotation of the spindle 10 by a handle 15 fixed to the outer end of the bearing shaft 12. The spindle 10 is tubular and is externally threaded, as at 16, the bore 90 95 17 thereof providing a guide into which a conduit 18, to be tapered, is projected.

Automatic feeding of a conduit to the cutters 9 is accomplished by a sleeve 19 threaded on the rotating spindle 10 and provided with thumb screws or other means 20 by which it may be clamped to the conduit. Arms 21 are extended from the sleeve 19 at diametrically opposite points and provide means for readily holding the sleeve and, consequently, the conduit against rotation as the spindle 10 is rotated by its handle or other means 15, rotation of the spindle 10 threading the same into the sleeve 19 drawing it towards the cutter members and thus evenly feeding the conduit into engagement therewith.

From the foregoing description, taken in connection with the accompanying drawings, it will be readily apparent to those skilled in the art to which an invention of the character described appertains, that a novel and improved device is provided for tapering the ends of conduits which is readily portable and by which the ends of conduits may be tapered in the field at the time of installation in an efficient and simple manner and in which automatic means are provided for evenly feeding the conduit into engagement with the cutting members.

What I claim as my invention is:

1. A portable tool for tapering the ends 30 of conduit members at the time of installation, comprising a supporting member, a spindle rotatably mounted in the supporting member, cutting members carried by the spindle, an exteriorly threaded projection 35 formed on the spindle providing a guide for receiving the end of the conduit member to be tapered, a sleeve threaded on said extension, means for clamping the conduit in the sleeve member, and means whereby the sleeve member may be restrained against rotation 40 as the spindle is rotated to draw the sleeve and consequently the conduit toward the cutting members.
2. A tool for tapering the ends of conduit 45 members, comprising a support, a spindle rotatable therein, revoluble cutters carried by the spindle, means for driving the cutters upon rotation of the spindle, a tubular extension on the spindle for receiving and guiding 50 the end portion of a conduit member to be tapered, a sleeve securable on the conduit member, means carried by the sleeve to facilitate holding the conduit member against rotation during operation of the tool, and a threaded 55 connection between the sleeve and the tubular spindle extension whereby the conduit member is evenly fed to the cutters as the spindle is rotated.

In testimony whereof I have hereunto affixed my signature.

ALWIN G. STEINMAYER.
